US00D902333S

(12) **United States Design Patent** (10) Patent No.: **US D902,333 S**
 Clarke et al. (45) Date of Patent: **** Nov. 17, 2020**

(54) **GOLF CLUB HEAD**(71) Applicant: **KARSTEN MANUFACTURING CORPORATION**, Phoenix, AZ (US)(72) Inventors: **Jacob T. Clarke**, Phoenix, AZ (US);
David A. Higdon, Cave Creek, AZ (US)(73) Assignee: **Karsten Manufacturing Corporation**, Phoenix, AZ (US)(**) Term: **15 Years**

FIG. 1 is a top perspective view of a golf club head;
 FIG. 2 is a bottom perspective view of the golf club head of FIG. 1;

FIG. 3 is a top view of the golf club head of FIG. 1;
 FIG. 4 is a bottom view of the golf club head of FIG. 1;
 FIG. 5 is a front view of the golf club head of FIG. 1;
 FIG. 6 is a rear view of the golf club head of FIG. 1;
 FIG. 7 is a heel side view of the golf club head of FIG. 1;
 and,
 FIG. 8 is a toe side view of the golf club head of FIG. 1.
 The broken lines show portions of the golf club head that form no part of the claimed design.
